(57) **CLAIM**

The ornamental design for a door lock, as shown and described.

DESCRIPTION

FIG. 1 is a top perspective view of embodiment 1 thereof; FIG. 2 is a bottom perspective view of embodiment 1 thereof;

FIG. 3 is a front view of embodiment 1 thereof;

FIG. 4 is a rear view of embodiment 1 thereof;

FIG. 5 is a left side view of embodiment 1 thereof;

FIG. 6 is a right side view of embodiment 1 thereof;

FIG. 7 is a top view of embodiment 1 thereof;

FIG. 8 is a bottom view of embodiment 1 thereof;

FIG. 9 is a top perspective view of embodiment 2 thereof;

FIG. 10 is a bottom perspective view of embodiment 2 thereof;

FIG. 11 is a front view of embodiment 2 thereof;

FIG. 12 is a rear view of embodiment 2 thereof;

FIG. 13 is a left side view of embodiment 2 thereof;

FIG. 14 is a right side view of embodiment 2 thereof;

FIG. 15 is a top view of embodiment 2 thereof; and,

FIG. 16 is a bottom view of embodiment 2.

The broken lines in the drawings illustrate the portions of the door lock, which form no part of the claimed design. The unshaded surfaces shown between solid and broken lines in FIGS. 1 and 9 form no part of the claimed design.

1 Claim, 16 Drawing Sheets
